STAND FOR FIRE ESCAPES

Filed Nov. 29, 1926

Fig. 1.

Fig. 2.

Fig. 3.

A diagram of a rectangular wooden block. On the left side, there is a vertical slot labeled '12'. On the right side, there is a circular hole labeled '10'. A small vertical line labeled '11' extends from the top edge of the block towards the circular hole.

William Kautz

Inventor

By Clarence A. O'Brien, Attorney

UNITED STATES PATENT OFFICE.

WILLIAM KAUTZ, OF WILLARD, OHIO.

STAND FOR FIRE ESCAPES.

Application filed November 29, 1926. Serial No. 151,479.

This invention relates to stands for fire escapes, and has for its primary object to provide a device of this character that is constructed for use in conjunction with a fire escape of the type shown and described in my copending application, Serial No. 151,480, filed on even date herewith.

By reason of the present invention said type of fire escape may be readily wound upon itself during the raising of the fire escape from the outside of a building, and be entirely out of the way and completely hidden from view when not in use.

The invention further aims to provide a stand of this character that may be employed as a table or desk and that may be quickly moved toward or away from the building window after the fire escape has been disposed therein, or in the event it becomes necessary to extend the fire escape upon the outside of the building.

A further and important object of the invention is to provide a device of this character wherein the fire escape may be let out of the window or drawn therein without contacting with the surface of the window sill which would otherwise mar and greatly damage the same.

Other objects will become apparent as the nature of the invention is better understood, the same comprising the novel form, combination, and arrangement of parts herein-after more fully described, shown in the accompanying drawing and claimed.

In the drawing wherein like reference characters indicate corresponding parts throughout the several views:

Figure 1 is a side elevation of a stand for fire escapes constructed in accordance with the present invention.

Figure 2 is a front elevation thereof.

Figure 3 is a detail vertical section disclosing the fire escape as associated therewith and in the act of being drawn through the window, and

Figure 4 is a perspective of one of the supporting blocks for the unit at the upper end of the fire escape generally disclosed herein and specifically shown and described in my previously mentioned co-pending application for patent.

Now having particular reference to the drawing, my novel stand consists of a top board 5 from the four corners of which depend supporting legs 6 that are equipped at their lower ends with rollers or casters 7 to

permit the stand to be readily moved from place to place. Suitably journaled beneath the top board 5 is a horizontal shaft 8, one end of which is equipped with a crank handle 9 at the side of the stand, while mounted upon the shaft within opposed sides thereof is a pair of similarly shaped blocks 10—10. These blocks are preferably of wood and are formed at their inner ends and at their top sides with projecting noses 11, the under sides of which are tapered as in Figure 4 for engagement within the hooked ends 16 of the arms 15 of the unit shown and described in my previously mentioned co-pending application after said unit is removed from the sill of the window B of the building A, which unit is adapted to be supported in its entirety upon said pair of blocks 10—10 as in Figure 3.

The outer ends of these blocks 10 are formed with vertical slots 12 within which the reinforced end plates of the arms 15 of said units engage for the purpose of preventing longitudinal sliding movement of the units upon said supporting blocks. Furthermore, each block 10 is provided at its upper edge with a hooked pin 13 that may be turned for engaging the hooked end thereof over the arm 15 as shown in Figure 3 to prevent the dropping of the unit from the block when said shaft 8 is rotated for winding the fire escape designated generally by the reference character C upon said unit.

Pivoted to the pair of legs adjacent the window when the stand is disposed in close proximity therewith when letting the chain out of the window or drawing the same therethrough is a pair of elongated arms 14—14 that are pivoted at their inner ends to the lower ends of said legs as clearly disclosed in Figures 1, 2 and 3. Adjacent their outer ends and at their outer edges, said arms 14 are formed with curved tongues 17 which are adapted for engagement with the inner sill board of the window B while the extreme outer ends thereof are equipped with a removable roller 18 over which the fire escape will pass, and upon which the same will be supported when letting the chain out of or drawing the same into the building.

Interconnecting the said units at the upper end of the fire escape and the block carrying shaft 8 is a chain length 19 provided for the purpose of preventing the entire dropping of the ladder from the building

and for facilitating the raising of the ladder should the unit for any reason become disengaged from the window sill B.

It will thus be seen that I have provided a highly novel, simple, and efficient fire escape that is well adapted for all the purposes heretofore designated, even though I have herein shown and described the invention as consisting of certain detail structural elements, it is nevertheless to be understood that minor changes may be made therein without effecting the spirit and scope of the appended claims.

Having thus described the invention, what I claim as new and desire to secure by Letters Patent is:—

1. In a cabinet for a flexible fire escape wherein a hook is carried by the upper end of the latter, a rotatable shaft journaled in the cabinet, a block secured on the shaft for rotation therewith, and cooperating means between the hook and said block for securing said members together whereby the flexible fire escape may be wound around the block and the shaft when the latter is rotated in one direction, said means including a nose projecting from one end of the block with which the hooked end of the hook engages, and a hooked pin carried by the block and adapted to extend over the shank of the hook.

2. In a cabinet for a flexible fire escape, wherein a hook is carried by the upper end of the latter, a rotatable shaft journaled in the cabinet, a block secured on the shaft for rotation therewith, the hooked end of said hook engaging over one end of the block, a hooked pin carried by the block and adapted to extend over the shank of the hook whereby the flexible fire escape may be wound

around the block, and the shaft when the latter is rotated in one direction, and additional means for connecting the hook to the shaft independently of the block of the shaft.

3. In a cabinet for a flexible fire escape, wherein a hook is carried by the upper end of the latter, a rotatable shaft journaled in the cabinet, a block secured on the shaft for rotation therewith, the hooked end of said hook engaging over one end of the block, a hooked pin carried by the block and adapted to extend over the shank of the hook whereby the flexible fire escape may be wound around the block, and the shaft when the latter is rotated in one direction, and additional means for connecting the hook to the shaft independently of the block of the shaft, said last mentioned means comprising a flexible connection between the hooked end of the hook and said block.

4. In a cabinet for a flexible fire escape wherein a hook is carried by the upper end of the latter, a rotatable shaft journaled in the cabinet, a block secured on the shaft for rotation therewith, a nose projecting from one end of the block with which the hooked end of the hook engages, the other end of the block being formed with a slot, a plate depending from the other end of the shank of the hook for disposition within the slot to prevent longitudinal sliding movement of the hook with respect to the block, said flexible fire escape being adapted to be wound around the block and the shaft when the latter is rotated in one direction, and a hooked pin carried by the block and adapted to extend over the shank of the hook.

In testimony whereof I affix my signature.

WILLIAM KAUTZ.
